WINDOW GREENHOUSE

Cyrus D'Amato, 8 Parkway Drive, Roslyn Heights, N.Y.

Filed Sept. 12, 1962, Ser. No. 71,657

Term of patent 14 years

(Cl. D35—3)

FIG. 2

FIG. 1 is a front perspective view of a window greenhouse embodying my new design, the top being in an open position, the fragmentary showing of a house being for purposes of illustration only; and

FIG. 2 is a rear perspective view thereof, the top being in a closed position.

The dominant features of my design reside in the full line portions of the drawing.

I claim:

The ornamental design for a window greenhouse, substantially as shown and described.
